UNITED STATES PATENT OFFICE.

WILLIAM OWEN, OF PITTSBURGH, PENNSYLVANIA, ASSIGNOR TO PITTSBURGH PLATE
GLASS COMPANY, A CORPORATION OF PENNSYLVANIA.

MULTIPLE-GROOVE-DRESSING DEVICE FOR ABRASIVE WHEELS.

Application filed March 18, 1926. Serial No. 95,691.

The invention relates to a device for dressing the multiple grooves in abrasive wheels, such as are employed for rounding the edges of glass sheets for use in automobile construction. Such machines comprise a series of grooved abrasive wheels with means for carrying a plurality of sheets of glass, corresponding to the number of grooves in the wheels, over such wheels, so that the edges 5 of the sheets are ground to a curvature which is complementary to that of the grooves. In the course of time, the grooves in the wheels are worn so that they lose their proper degree of curvature, and it becomes 10 necessary to dress or resurface them back to their original shape. This is done by means of a tool, including a rod of abrasive of circular cross section having its working end rounded to the proper curvature. Each 15 groove is in turn subjected to the action of the tool until the surface of the wheel is restored to substantially its original contour. This operation is relatively slow and tedious, requiring considerable skill, and involving a high labor cost, as the resurfacing 20 is required after only a short period of use of the wheels, otherwise, the quality of the product is impaired, and many of the glass sheets must be sent through the machine a 25 second time. The object of the present invention is the provision of a dressing attachment, which can very readily be applied and removed from existing machines, and which 30 will permit the accurate resurfacing of the grooves of the wheel simultaneously, and with minimum expenditure of time and effort on the part of the operator. One embodiment of the invention is illustrated in the accompanying drawings, wherein:

Figure 1 is a vertical section on the line I—I of Fig. 2. Fig. 2 is a section on the line II—II of Fig. 1. Fig. 3 is a plan view. And Fig. 4 is a detail section.

Referring to the drawings, 1 is an annular grinding wheel supported in a spider or frame 2 carried upon a shaft 3, such wheel being provided with a plurality of circumferential grooves 4, 4, 4, etc. Extending longitudinally of the line of movement of 45 the glass sheets to be ground at the sides of the grinding wheel is a guideway made up of the plates 5 and 6, such plates being provided with the flanges 7, 8 and 9 (Fig. 50 2). This guideway serves to carry the drag chain and cooperating devices for engag-

ing the series of plates to be ground and carrying them longitudinally over the series of grinding wheels, the construction being one in extensive use and well known to those skilled in the art. The guide plate 5 also 60 carries a longitudinally extending wood strip 10 suitably secured in position. This guideway is utilized as a support for the dressing device to which the invention is particularly directed and which will now be 65 described.

The framework of the dressing device comprises a casting including a pair of angular members 11 and 12 and the horizontal plate 13, held upon the guide members 5 and 6 by means of the pairs of bolts 15, 15 and 16, 16. The bolts 15, 15 are provided with nuts 17 and have hook ends at their lower extremities, as indicated in Fig. 4, for engaging the lower side of the plate 5. The bolts 16, 16 extend through the vertical flange of the member 12 and engage the upstanding flange 9 on the plate 6. Means are thus provided for clamping the supporting frame of the dressing device rigidly in position above 70 the grinding wheel, the means shown for accomplishing this purpose permitting of the ready attachment of the device and its detachment after the device has performed 75 its function.

Pivotedly supported upon a transverse bolt 14 carried by the frame members 11 and 12 is an arm 18, such arm being provided with a plurality of abrasive dressing sticks or rods 19, 19, 19, etc. The arm is adjusted up 80 and down by means of the bolt 20 and the nut 21, the bolt having its head 22 (Fig. 1) loosely mounted in the end of the plate 13. A spring lock member 23 secured to the plate 13 by means of the screw 24 engages a 85 slot in the head 22 and prevents its rotation. A spring 25 presses the arm 18 yielding upward. The rotation of the nut 21 serves to adjust the arm 18 up and down 90 and to bring the lower rounded ends of the abrasive sticks 19 into operative engagement with the grooves in the wheel 1.

The abrasive sticks 19 are carried in split chucks 26 mounted in the sleeves 27, conical cooperating surfaces being provided at 28, so that when the chuck is pulled upwards, it 95 is clamped tightly against the stick 19. The chuck is moved vertically by means of a hollow rod 29 which is secured in the block 30 integral with the upper end of the chuck. 100 105 110

A nut 31 provides for the vertical adjustment of the rod 29, such nut being seated upon the upper end of the sleeve 27. The abrasive stick 19 is adjusted and held in position by means of a screw 32 extending through the rod 31 and provided with a head 33 at its upper end for turning it. This screw is threaded through the screw 29 and serves to adjust the position of the rod 10 and to fix it against vertical movement. The upper ends of the sleeves 27 have secured thereto by means of the keys 27^a the spur pinions 34, 34, 34, etc., all meshing together in a series, as indicated in Fig. 3, so 15 that when one of the sleeves is turned, a similar rotation of all of the sleeves is secured. The upper end of one of these sleeves is provided with the rotating knob or handle 35, and by rotating this knob, all of the 20 dressing sticks are rotated, so that the wear at the lower ends of the abrading rods is distributed over such ends and their rounded shape is preserved throughout a long period of use.

25 In operation the frame carrying the dressing device is clamped securely in position over the grinding wheel, as indicated in Figs. 1 and 2, and each of the dressing rods 19 is adjusted downward so that it contacts 30 with the surface of a groove in the grinding wheel. The chucks 26 are then all tightened and the feed knob 21 is rotated by the operator to cause the ends of the rods 19 to engage the surface of the grooves with a 35 slight amount of pressure. At the same time, the knob 25 is rotated by the operator so as to shift the surfaces at the ends of the rods 19 and bring different portions thereof in contact with the surface of the grooves 40 which are being dressed. The downward adjustment by means of the knob 21 and the rotary movement of the knob 35 are continued until each of the grooves is properly dressed, after which the device is removed 45 from its position upon the guide plates 5 and 6, and the grinding wheel is ready for service.

What I claim is:

1. A dressing device, comprising a frame 50 releasably secured to the work guideway of

a grooved abrading wheel, an arm pivoted to said frame for movement toward and from the wheel, an adjusting device for the arm, a plurality of dressing rods of abrasive material carried by the arm and adapted to engage the various grooves in the abrading wheel, each of said rods being mounted for rotation about its axis, and gear means for rotating the rods in unison. 55

2. A dressing device, comprising a frame 60 releasably secured to the work guideway of a grooved abrading wheel, an arm pivoted to said frame for movement toward and from the wheel, an adjusting device for the arm, a plurality of dressing rods of abrasive material carried by the arm and adapted to engage the various grooves in the abrading wheel, each of said rods being mounted for rotation about its axis, and hand operated 65 gear means for rotating the rods in unison. 70

3. A dressing device, comprising a frame 75 releasably secured to the work guideway of a grooved abrading wheel, an arm pivoted to said frame for movement toward and from the wheel, an adjusting device for the arm, a plurality of dressing rods of abrasive material carried by the arm and adapted to engage the various grooves in the abrading wheel, each of said rods being mounted for rotation about its axis gear means connecting all of the rods, and a hand device for actuating said gear means for rotating the rods in unison. 80

4. A dressing device, comprising a frame 85 releasably secured to the work guideway of a grooved abrading wheel, an arm pivoted to said frame for movement toward and from the wheel, an adjusting device for the arm, a plurality of chucks mounted for rotation in the arm, a rod of abrasive material mounted 90 for longitudinal adjustment in each chuck, intermeshing gear wheels carried by the chucks so that they may be rotated together, and means mounted for rotation with one of the chucks for rotating it. 95

In testimony whereof, I have hereunto subscribed my name this 12th day of March, 1926.

WILLIAM OWEN.
